THIENYLALKYL ESTERS

Frederick F. Blicke, Ann Arbor, Mich., assignor
to Regents of The University of Michigan, Ann
Arbor, Mich., a corporation of Michigan

No Drawing. Application September 9, 1946,
Serial No. 695,811

14 Claims. (Cl. 260—329)

1
This invention relates to certain basic-alkyl esters of substituted (alpha-thienyl) aliphatic acids, the salts of such esters, and pharmaceutical products in which they are employed as active ingredients. This application is a continuation-in-part of my prior-filed copending application Serial 575,929, filed February 2, 1945, which has been abandoned.

One of the principal objects of the present invention is the provision of a series of compounds having utility as pharmaceuticals and particularly as antispasmodic agents. Members of this new group of compounds have been prepared, identified and found to have value as antispasmodics and as the active ingredients in antispasmodic preparations for the relief of muscle spasm as determined by the method of Magnus (Archiv. der gesammte Physiologie, 1905, vol. 108, pages 1-71). The free basic esters of this group of compounds are usually oily liquids with relatively high boiling points, while the acid or quaternary ammonium salts thereof are usually crystalline solids at ordinary temperatures.

The basic-alkyl esters of the present invention have the following generic formula:

wherein R represents hydrogen or a hydrocarbon radical, m represents zero or a positive integer from 1 to 5, inclusive, the carbon chain is straight or branched and contains from 1 to 8 carbon atoms, inclusive, X is hydrogen or a hydroxy radical, and Z is a primary or secondary amine radical.

Within the meaning of R in the above formula I include such hydrocarbon radicals as alkyl radicals, for example, methyl, isopropyl and n-octyl; aryl radicals, such as phenyl, naphthyl and para-xenyl; cycloalkyl radicals, such as cyclohexyl; cycloalkylalkyl radicals, such as cyclohexylethyl and cyclohexylmethyl; aralkyl radicals, such as phenethyl, phenmethyl; alkaryl radicals, such as ethylphenyl; alkylcycloalkyl radicals, such as ethylcyclohexyl; alkylcycloalkylalkyl radicals, such as methylcyclohexylethyl; and alkylaralkyl radicals, such as ethylphenylmethyl. Such hydrocarbon radicals preferably

contain not more than twelve carbon atoms, regardless of the structure of the substituent.

The primary and secondary amine radicals represented by Z include such radicals as mono-methylamino, monoethylamino, monopropylamino, isopropylamino, monobutylamino, n-octylamino, monocyclohexylamino, diethylamino, di-isopropylamino, dibutylamino, dicyclohexylamino, diphenylamino, phenylethylamino, and the like.

10 The compounds included within the scope of the present invention include (a) compounds of the above general formula and (b) salts thereof.

The term "salts" includes acid salts, such as the citrate, tartrate, hydrochloride, hydrobromide, hydrosulfate, and many others, as well as the quaternary ammonium salts, such as the methobromide, ethochloride and ethyl paratoluene-sulfonate. The acid salts may be prepared from

15 the free basic ester by treatment with the selected acid, while the quaternary ammonium salts are prepared by treatment of the free basic ester with the desired alkyl halide or aryl sulfonic ester. When the ester is formed by a reaction of an acid and an alkyl halide, or by the reaction of an acid halide and an alcohol, the ester usually

20 precipitates as the hydrohalide salt.

The hydrocarbon-substituted thiénylaliphatic acids employed as starting materials may be prepared by first reacting thiophene with an acid halide of a monoester of oxalic acid, e. g., ethyl oxalyl chloride, $\text{C}_2\text{H}_5\text{COCl}$, in the presence of aluminum chloride, to produce an alkyl ester of an alpha-thienyl keto acid, such as ethyl (alpha-thienyl) glyoxylate,

25 The keto acid, obtained by hydrolysis of the ester, is then reacted with a Grignard reagent containing the selected hydrocarbon radical and the resulting complex is decomposed with a suitable acidic reagent, such as HCl , NH_4Cl , NaHSO_4 , et cetera, to produce a substituted thiényl hydroxyaliphatic acid having a hydrocarbon radical attached to a carbon atom of the aliphatic chain. This compound may be employed without further modification in the production of the hydroxy-containing basic ester, or it may be reduced, e. g., with stannous chloride, to produce the corresponding hydroxy-free hydrocarbon-substituted

thienylaliphatic acid and thereafter treated to prepare the basic ester.

As an alternative procedure, the acyl halide of the alkyl monoester of oxalic acid may first be reacted with a suitable hydrocarbon such as benzene, biphenyl(para-xenyl radical) naphthalene, et cetera, in the presence of aluminum chloride, to produce the corresponding substituted keto acid, the latter hydrolysed to the free acid, and the acid then reacted with a Grignard reagent containing a thiienyl radical. Decomposition of the magnesium-containing complex with acid and reduction of the hydroxy acid may be carried out as described in the preceding paragraph.

The preparations and examples herein will serve to illustrate procedure whereby production of members of this new group of compounds may be accomplished, but are in no way to be construed as limiting.

PREPARATION 1.—ETHYL (ALPHA-THIENYL) GLYOXYLATE

A mixture of 84 grams (1 mole) of thiophene, 137 grams (1 mole) of ethyl oxalyl chloride and 1500 milliliters of tetrachloroethane was cooled to minus 5 degrees centigrade and 147 grams (1.1 moles) of aluminum chloride was added portionwise thereto with stirring over a period of forty-five minutes. The mixture was stirred for three hours at room temperature and allowed to stand an additional five hours. The mixture was then treated with ice and hydrochloric acid. The organic layer was separated, washed successively with 1:1 hydrochloric acid, water, dilute sodium carbonate solution, and water. The washed layer was then dried with anhydrous sodium sulfate, and fractionally distilled. A yield of 93 grams of ethyl (alpha-thienyl) glyoxylate, boiling at 115-120 degrees centigrade at three millimeters of mercury pressure absolute, was obtained.

dryness. Upon recrystallising the residue from benzene, there was obtained 24 grams of (alpha-thienyl) glyoxylic acid melting at 89-91 degrees centigrade.

5 PREPARATION 3.—SUBSTITUTED HYDROXY ACIDS

A solution of methyl magnesium iodide (prepared by reacting 85.2 grams (0.6 mole) of methyl iodide with 14.4 grams (0.6 mole) of magnesium in 300 milliliters of diethyl ether) was added dropwise and with stirring to 31.2 grams (0.2 mole) of (alpha-thienyl) glyoxylic acid dissolved in 300 milliliters of ether and cooled with a mixture of ice and salt. An immediate vigorous reaction occurred and a precipitate separated. The mixture was stirred for one hour at room temperature, heated to boiling under reflux for two hours, cooled, and the ether layer decanted and discarded. The granular residue was washed with ether, decomposed with dilute sulfuric acid, extracted with ether, and the ether extract washed with an excess of aqueous twenty per cent sodium carbonate solution. The alkaline wash liquor was clarified with activated carbon, filtered, and the filtrate acidified with dilute sulfuric acid. The precipitate was separated, washed with ether, and dried. After recrystallisation from benzene there was obtained 30 grams of methyl-(alpha-thienyl) hydroxyacetic acid melting at 111-113 degrees centigrade.

By substituting cyclohexyl, benzyl, phenyl, para-xenyl, alpha-naphthyl, phenethyl, cyclohexylethyl or similar magnesium halides, for the methyl magnesium iodide employed in the preparation just described, the corresponding substituted (alpha-thienyl) hydroxyacetic acids are obtained.

In Table I there are given the melting points, empirical formulae, and analyses of representative hydroxy acids employed in accordance with the present invention.

² Recrystallised from dilute acetic acid.

³ Decomposed.

PREPARATION 2.—(ALPHA-THIENYL) GLYOXYLIC ACID

A mixture of 40 grams of ethyl (alpha-thienyl) glyoxylate, 75 milliliters of ethanol, 58 grams of sodium carbonate monohydrate, and 450 milliliters of water was refluxed for twelve hours. The hot solution was clarified with activated carbon and the alcohol and water removed by distillation under reduced pressure. The residue was cooled and acidified with 1:1 cold hydrochloric acid, extracted with ether, and the ether extract washed with water and evaporated to

PREPARATION 4.—NON-HYDROXY ACIDS

In the preparation of thienyl-substituted fatty acids from the hydroxy acids just described, the latter are reduced, preferably with stannous chloride. In a representative operation, 12 grams (0.051 mole) of phenyl-(alpha-thienyl) hydroxyacetic acid, 24 grams (0.106 mole) of stannous chloride dihydrate and 200 milliliters of acetic acid were stirred together. Hydrogen chloride was passed into the mixture with agitation at 15 degrees centigrade. After three hours, the mixture was blown with air to remove acetic acid,

the residue mixed with ice-water and filtered. The residue, after washing with water and recrystallising from fifty per cent acetic acid, weighed 7 grams and consisted of phenyl-(alpha-thienyl) acetic acid.

In Table II there are given the melting points, empirical formulae, and analyses of representative hydrocarbon-substituted (alpha-thienyl) acetic acids employed as reactants in preparing the compounds of the invention. The compounds were purified by recrystallising from dilute acetic acid.

PREPARATION 5.—ALPHA-THIENYLMETHYL CHLORIDE

A rapid stream of hydrogen chloride was passed into a stirred mixture of 525 milliliters of concentrated hydrochloric acid, 450 milliliters of 40 per cent aqueous formaldehyde, and 465 milliliters of thiophene at a temperature between zero and five degrees centigrade. After saturation with the gas, the material was poured into two liters of water, the oily precipitate separated, and the aqueous layer extracted several times with ether. Extracts and the oil were combined, washed with water and dried over potassium carbonate. After removal of the ether, the product boiled at 78-82 degrees centigrade at 18 milliliters of mercury pressure. The yield was 373 grams, or 47 per cent of the theoretical.

The chloride should not be kept in a tightly closed container since it undergoes spontaneous decomposition, often with explosive violence. If preserved in a refrigerator, the compound remains undecomposed for some time.

PREPARATION 6.—(ALPHA-THIENYL)ACETONITRILE

A mixture of 133 grams of (alpha-thienyl)-methyl chloride, 60 milliliters of acetone, and 74 grams of sodium cyanide dissolved in 100 milliliters of water, stirred and heated in a water-bath at 60-65 degrees centigrade for four hours. Water was added, the organic layer separated and added to the ether extract of the aqueous layer. The ether was removed from the dried solution and the nitrile distilled. The nitrile boiled at 115-120 degrees centigrade at 22 milliliters of mercury pressure. The yield was 100 grams, or 81 per cent of the theoretical.

PREPARATION 7.—(ALPHA-THIENYL)-ACETATE

A mixture of 100 grams of (alpha-thienyl)-acetonitrile, 225 milliliters of 95 per cent alcohol and 7 milliliters of water was poured into a citrate bottle and saturated with hydrogen chloride at a temperature between zero and five degrees centigrade. After 12 hours at room temperature, the mixture was heated for two hours on a steam-bath, cooled, 150 milliliters of water added, and the oily layer separated and added to the ether extract of the aqueous layer. The

solution was dried and the solvent removed. The desired product was obtained in 66 per cent yield (93 grams) and boiled at 119-121 degrees centigrade at 23 milliliters of mercury pressure.

5 PREPARATION 8.—BETA'-(ALPHA-THIENYL)ETHYL CHLORIDE

A solution of (alpha-thienyl) magnesium bromide, prepared from 97.8 grams of alpha-bromo-thiophene, 14.6 grams of magnesium and 375 milliliters of ether, was stirred and 280 grams of beta-chloroethyl (para-toluene) sulfonate, dissolved in 300 milliliters of ether, was added drop-

wise thereto. A solid began to precipitate after about one-half of the ester had been added. The mixture was stirred and refluxed for five hours, cooled to between five and ten degrees centigrade, and 100 milliliters of concentrated hydrochloric acid diluted with 350 milliliters of water was added thereto. An amount of water sufficient to dissolve the precipitate was then added and the ether layer was washed with sodium bicarbonate solution and dried with potassium carbonate. The chloride boiled at 88-92 degrees centigrade at 20 milliliters of mercury pressure. The yield was 62.6 grams, or 71.4 per cent of the theoretical. The analysis showed C₆H₇SCl to contain 24.06 per cent chloride as compared with the theoretical of 24.19.

PREPARATION 9.—MONOSUBSTITUTED MALONIC ESTERS

For the preparation of diethyl (alpha-thienyl)-malonate and diethyl phenylmalonate, the procedure of Wallingford et al. (Wallingford, Homyer and Jones, J. Am. Chem. Soc., 63, 2056 (1931)) for the latter compound was employed. It was found that simple apparatus consisting only of a three-neck, 500-milliliter flask fitted with inclined condenser and sealed stirrer was satisfactory. Excess diethyl carbonate was used due to unavoidable loss of this substance from the reaction mixture during removal of the alcohol.

To obtain diethyl (alpha-thienyl) malonate, a solution of sodium ethylate, prepared from 18.5 grams of sodium and 300 milliliters of alcohol, was heated in an oil-bath, stirred and the alcohol removed under reduced pressure. The cake of sodium ethylate was broken into small pieces and 650 milliliters of diethyl carbonate, followed by 132.4 grams of ethyl (alpha-thienyl)-acetate, was added. The mixture was stirred at 80-85 degrees centigrade and the alcohol was removed, as fast as formed, at 300-320 milliliters of mercury pressure. After five hours the distillate, a mixture of alcohol and diethyl carbonate, amounted to about 200 milliliters. The material was poured into a mixture of water and ice to which 90 milliliters of concentrated hydrochloric acid had been added. The organic layer was separated, combined with the benzene extract of the aqueous layer, and shaken with water. After removal of excess benzene and diethyl carbonate,

the diethyl (alpha-thienyl) malonate (117 grams) boiled at 148-151 degrees centigrade at 6 millimeters of mercury pressure.

By the employment of the same procedure, diethyl phenylmalonate was obtained in 83 per cent yield.

All other monosubstituted malonic esters were prepared by the procedure used for diethyl beta-(alpha-thienyl) ethylmalonate described below.

PREPARATION 10.—DIETHYL BETA'-(ALPHA-THIENYL)-ETHYLMALONATE

A solution of sodium ethylate, prepared from 7.8 grams of sodium and 135 milliliters of ethanol,

10

was warmed to 50 degrees centigrade and 32 grams of diethyl cyclohexylmethylmalonate (8 in Table III hereinafter), was added. After the mixture had refluxed for a few minutes, 24.9 grams of (alpha-thienyl)methyl chloride was added dropwise at a rate such that the mixture continued to reflux. After about three hours at reflux, the product was isolated in the usual manner.

The boiling points of some of the thus-prepared mono- and disubstituted malonic esters are given in Table III.

Table III

was warmed to 50 degrees centigrade and 81.5 grams of diethyl malonate was added thereto. The mixture was heated to the boiling point and 50.5 grams of beta'-(alpha-thienyl) ethyl chloride was added slowly. The mixture was refluxed for twenty hours, alcohol removed under reduced pressure, water added to the oily residue, and the mixture neutralized with dilute hydrochloric acid. The organic layer was separated and combined with the benzene extract of the aqueous layer. After removal of solvent, the ester boiled at 150-154 degrees centigrade at 4 millimeters of mercury pressure. The yield was 46.7 grams or 51 per cent of the theoretical.

PREPARATION 11.—DISUBSTITUTED MALONIC ESTERS

Diethyl beta-cyclohexylethyl-(alpha-thienyl)-methylmalonate and diethyl cyclohexyl-(alpha-thienyl) methylmalonate were obtained by the method described below for the latter ester.

The alcohol was removed under reduced pressure from a solution of sodium ethylate and 200 milliliters of diethyl carbonate and 48.4 grams of diethyl cyclohexylmalonate was added. The mixture was heated in a bath at 60-65 degrees centigrade under 200 millimeters pressure. After about 40 milliliters of alcohol and diethyl carbonate had distilled, 31.0 grams of (alpha-thienyl)methyl chloride was added, the mixture heated at 100-105 degrees centigrade for three hours, and the product (46.0 grams, 68 per cent) isolated in the usual manner.

Other disubstituted malonic esters are prepared by the method described below for (alpha-thienyl)methyl-cyclohexylmethylmalonate, by substituting the selected reactants for those given below.

PREPARATION 12.—(ALPHA-THIENYL)-METHYL-CYCLOHEXYL METHYLMALONATE

A solution of sodium ethylate, obtained from 4.3 grams of sodium and 140 milliliters of alcohol,

(alpha-thienyl)methyl chloride was used to prepare all the disubstituted esters except 3', 4', and 5'; benzylchloride was employed for 3', beta-phenethyl bromide for 4', and beta-cyclohexylethyl bromide for 5'. Each disubstituted ester was obtained from the monosubstituted ester indicated by a corresponding number.

When this compound (C₆H₅SCH₂—CH(COOC₂H₅)₂) was hydrolyzed with a mixture of water, alcohol and potassium hydroxide, it yielded (alpha-thienyl)methylmalonic acid; M. P. 138-139 degrees centigrade after recrystallization from an acetone-benzene mixture. Analysis: Calculated for C₈H₈O₄S: S, 16.01. Found: S, 15.77.

This substance (C₆H₅SCH₂—CH(COOC₂H₅)₂) was converted by hydrolysis into beta-(2-thienyl)ethylmalonic acid; M. P. 130-131 degrees centigrade after recrystallization from acetone-benzene. Analysis: Calculated for C₉H₁₀O₄S: S, 14.97. Found: S, 14.90.

^a Cyclohexyl.

The preparation of malonic acids and acetic acids is further illustrated by the following procedure.

PREPARATION 13.—(ALPHA-THIENYL)-METHYL-CYCLOHEXYL METHYLMALONIC ACID

A mixture of 30.5 grams of diethyl (alpha-thienyl)-methyl-cyclohexylmethylmalonate, prepared according to the foregoing methods, and 19.6 grams of potassium hydroxide, dissolved in 20 milliliters of water and 78 milliliters of alcohol, was refluxed for twenty hours. The water and alcohol were then removed under reduced pressure, the residue dissolved in a small amount of water, the solution cooled to about five degrees centigrade, 50 milliliters of ether added, and the mixture acidified with concentrated hydrochloric acid. The ether layer was separated and mixed with the ether extract of the aqueous layer. After washing the ether solution with water, it was dried over magnesium sulfate and the solvent removed to give the desired product in a yield of about 80 per cent.

PREPARATION 14.—(ALPHA-THIENYL)-METHYL-CYCLOHEXYL METHYLMALIC ACID, ET CETERA

Ten grams of the corresponding malonic acid was heated to 175-185 degrees centigrade for a period of about one hour and the material thereafter distilled. The yield of the desired substituted acetic acid is usually of the order of 77 per cent of the theoretical.

Some substituted thiethylmethylmalonic and thiethylmethylacetic acids thus prepared and physical constants thereof are given in Table IV.

* Cyclohexyl.

Malonic acids 1 and 5 lost carbon dioxide spontaneously with the formation of the corresponding acetic acid.

Malonic acid 2 was recrystallised from water, 3 and 4 from a mixture of benzene-acetone, and 30 6, 7 and 8 from a mixture of petroleum ether.

Acetic acid 2 was recrystallised from a mixture of benzene and petroleum ether; all other acetic acids from petroleum ether.

In the preparation of the hydrohalides of the basic-alkyl esters of the hydrocarbon-substituted thiethyl aliphatic acids, substantially equimolar proportions of a basic-alkyl halide and the hydrocarbon-substituted thiethylaliphatic acid are admixed in a suitable solvent, e. g., ethanol or isopropyl alcohol, and the mixture heated until reaction has occurred. This may occur at room temperature or require heating at reflux for some time, e. g., 4 to 16 hours, more or less. The crude salt may be crystallised by dissolving it in a small quantity of warm ethanol, adding diethyl ether until turbidity and thereafter cooling the mixture. The salt separates in crystalline form and is recovered by decantation or filtration. Other acid salts may be obtained in a similar manner from the free basic ester. As the anti-spasmodic activity of the esters apparently resides in the ester itself, and not in the salt portion of the molecule, any acid may be employed without detracting materially from the effectiveness of the compound, provided only that the anion of the acid employed be reasonably non-toxic, and therefore the salt to be produced is usually chosen primarily with regard to crystallinity and solubility.

As an alternative method of salt formation, a non-hydroxy acid may be converted to the acid chloride, as by heating with thionyl chloride, and the acid chloride then reacted with the selected basic alcohol to form the desired ester hydrochloride. The former method is preferred, however, since higher yields of product are obtained thereby.

The free basic-alkyl esters may be obtained from the hydrohalides by treatment with aqueous sodium carbonate or other mild alkali, preferably at low temperatures, and thereafter extracting with ether or other suitable solvent. The solvent

free base may be warmed with alkyl halides, such as methyl bromide, ethyl chloride, propyl iodide, et cetera, or with the selected aryl sulfonic ester such as ethyl para-toluene-sulfonate, under which conditions the corresponding quaternary salt is usually formed in high yields.

EXAMPLE 1.—3-DIETHYLAMINOPROPYL PHENYL-(ALPHA-THIENYL)HYDROXY ACETATE HYDROCHLORIDE

A mixture of 3.4 grams of phenyl-(alpha-thienyl)hydroxy acetic acid, 2.2 grams of 3-diethylaminopropyl chloride and 50 milliliters of isopropyl alcohol was refluxed for twelve hours. 35 After 100 milliliters of absolute alcohol had been added to the cold mixture, it was treated with Norite activated carbon at room temperature, filtered, and the Norite treatment repeated several times. The solvents were removed from the filtrate under reduced pressure, and the residue rubbed under absolute ether. The crude ester hydrochloride (4.6 grams) was recrystallised from a mixture of absolute alcohol and absolute ether; melting point, 142-145 degrees centigrade.

EXAMPLE 2.—3-DIETHYLAMINOPROPYL PHENYL-(ALPHA-THIENYL)ACETATE HYDROCHLORIDE

A mixture of 2.7 grams (0.0125 mole) of phenyl-(alpha-thienyl)acetic acid, 1.7 grams (0.0125 mole) of 3-diethylaminopropyl chloride and 50 milliliters of isopropyl alcohol was refluxed for twelve hours. The cold solution was mixed with 150 milliliters of absolute alcohol, shaken with 60 Norite at ordinary temperature, filtered, the filtrate treated again with Norite, and the mixture filtered. The solvents were removed under reduced pressure, and the residue rubbed under absolute ether. The crude ester hydrochloride (2.5 grams) was recrystallised several times from benzene; melting point 87-89 degrees centigrade.

EXAMPLE 3.—2-DIETHYLAMINOETHYL (PARA-XENYL)-(ALPHA-THIENYL)ACETATE HYDROCHLORIDE

A mixture of 4.4 grams (0.015 mole) of (para-xenyl)-(alpha-thienyl)acetic acid and 5.5 milliliters of pure thionyl chloride was refluxed for one and one-half hours in an oil bath. After 75 the addition of 10 milliliters of dry benzene to

may then be dried and volatilized in accordance with conventional methods.

To produce quaternary ammonium salts, the

the dark brown mixture which contained the acid chloride, the benzene and excess thionyl chloride were removed under reduced pressure. Another 10 milliliters of benzene was added, removed by distillation, and this process repeated several times. The residue was cooled and dissolved in 15 milliliters of benzene. To the solution there was added, slowly, 2.0 grams of 2-diethylaminoethanol, and the mixture was refluxed for two hours. The solvent was removed under reduced pressure. The residue, a dark red, viscous mass, was dissolved in 200 milliliters of absolute alcohol and the solution treated with Norite several times. The solvent was removed under diminished pressure, and the light greenish-yellow, oily ester hydrochloride was rubbed under absolute ether until it became crystalline. It was recrystallised from a mixture of absolute alcohol and absolute ether; melting point 101-103 degrees centigrade.

EXAMPLE 4.—2-DIETHYLAMINOETHYL PHENYL-(ALPHA-THIENYL)HYDROXY-ACETATE HYDROCHLORIDE

Phenyl-(alpha-thienyl)hydroxyacetic acid (4.86 grams), 2-diethylaminoethyl chloride (2.85

EXAMPLE 5.—2-DIETHYLAMINOETHYL PHENYL-(ALPHA-THIENYL)ACETATE HYDROCHLORIDE

5 A mixture of 4.36 grams of phenyl-(alpha-thienyl)acetic acid, 2.75 grams of 2-diethylaminoethyl chloride and 40 milliliters of isopropyl alcohol was refluxed for 15 hours. Isopropyl alcohol was removed under reduced pressure, the residue dissolved in absolute alcohol, decolorized with Norite, filtered and alcohol removed by distillation. The residue was rubbed under absolute ether whereupon crystallisation began. The hydrochloride melted at 98-100 degrees centigrade.

10 In Table V are given the melting points (and in some cases, the boiling points) of some esters and salts thereof which are representative of the present invention.

^a hydrobromide. ^b methobromide. ^c free base, B. P., °C. ^d cyclohexyl. ^e para-xenyl. ^f decomposed.

grams) and 75 milliliters of isopropyl alcohol were refluxed for 15 hours. After the addition of 50 milliliters of absolute alcohol to the cold mixture, it was treated with Norite (activated charcoal) at room temperature, filtered, and the solvents removed under reduced pressure. The residue crystallised when triturated with absolute ether. After recrystallisation from absolute alcohol, the hydrochloride melted at 181-182 degrees centigrade.

Still another procedure which may be employed for the production of some of the esters involves the preparation of the desired acid halide, such as (alpha-thienyl)methyl-benzylacetil chloride (B. P., 170-175 °C. at 5 mm.), preparation of an amide, e. g., N-methyl-N-(beta'-hydroxyethyl)-(alpha-thienyl)methyl-benzylacetamide (B. P., 185-190 °C. at 0.05 mm., M. P., 55-57 °C.), by reaction of the acid chloride with the selected 70 aminoalkanol in an aqueous alkaline medium,

and conversion of the amide into the ester according to the directions of Reasonberg and Goldberg, J. Am. Chem. Soc. 67, 933 (1945). 2-methylaminoethyl (alpha-thienyl)methyl-benzylacetate hydrochloride, prepared in this manner, melts at 130-131 degrees centigrade.

Other compounds within the scope of the present invention include 2-butylaminoethyl (alpha-thienyl) acetate hydrochloride, 3-aminopropyl (alpha-thienyl) acetate hydrobromide, 2-ethylamino (alpha-thienyl) butylacetate ethochloride, 4-ethylaminobutyl (alpha-thienyl) propylacetate ethyl (para-toluene)sulfonate, 2-dipropylaminoethyl (alpha-thienyl) propyl-phenethylacetate hydrobromide, 5-diethylaminoamyl (alpha-thienyl) butyl-ethylcyclohexylacetate hydro-sulfate, 2-ethylaminoethyl (alpha-thienyl) methyl-ethylphenylacetate hydrochloride, 2-cyclohexylethylaminoethyl (alpha-thienyl)-methyl-phenethylacetate hydrochloride, 2-dimethylaminoethyl (alpha-thienyl) methyl-ethylcyclohexyl-ethylacetate hydrochloride, 2-diethylaminoethyl (alpha-thienyl) acetate hydrochloride, 2-diethylaminoethyl (alpha-thienyl) ethyl-hydroxyacetate hydrochloride, and the like, all of which may be prepared according to the foregoing disclosure.

The preferred embodiment of the present invention resides in compounds of the formula

wherein m , X , the carbon chain, and Z have the values previously given, and wherein R is hydrogen or a hydrocarbon radical selected from the group consisting of alkyl, aryl, cycloalkyl, aralkyl and cycloalkylalkyl, which compounds have exhibited exceptional antispasmodic activity. Some of the compounds also exhibit local anesthetic and mydriatic effects.

Attention is directed to my application Serial No. 125,380, filed November 3, 1949, in which is claimed subject matter disclosed but not claimed herein.

It is to be understood that many variations may be made without departing from the spirit and scope of the invention, and that I am to be limited only by the appended claims.

I claim:

1. A compound selected from the group consisting of (a) basic-alkyl esters of the formula

wherein R represents a hydrocarbon radical, m represents a number from 0 to 5, inclusive, the carbon chain is straight or branched and contains from 1 to 8 carbon atoms, inclusive, X is selected from the group consisting of hydrogen and hydroxy radicals, and Z is selected from the group consisting of primary and secondary amine radicals, and (b) salts thereof.

2. A compound selected from the group consisting of (a) basic-alkyl esters of the formula

wherein R represents a carbocyclic hydrocarbon radical, m represents a number from 1 to 5, inclusive, the carbon chain is straight or branched and contains from 1 to 8 carbon atoms, inclusive, X is selected from the group consisting of hydrogen and hydroxy radicals, and Z is selected from the group consisting of primary and secondary amine radicals, and (b) salts thereof.

3. A salt of a compound having the formula

wherein R represents a six-carbon-atom carbocyclic hydrocarbon radical, m represents a number from 1 to 5, inclusive, the carbon chain is straight or branched and contains from 1 to 8 carbon atoms, inclusive, X is selected from the group consisting of hydrogen and hydroxy radicals, and Z is selected from the group consisting of primary and secondary amine radicals.

4. A compound as defined in claim 3, wherein R is the phenyl radical.

5. A compound as defined in claim 3, wherein R is the cyclohexyl radical.

6. A compound as defined in claim 1, in which Z is a lower dialkylamino radical, and m represents the number 1.

7. A compound as defined in claim 3, in which R is a lower alkyl radical.

8. A compound as defined in claim 3, in which R is a benzyl radical.

9. A compound as defined in claim 3, in which R is a cyclohexylmethyl radical.

10. 2-diethylaminoethyl cyclohexyl-(alpha-thienyl)methylacetate hydrochloride.

11. 2-diethylaminoethyl phenyl-(alpha-thienyl)methylacetate hydrobromide.

12. 2-diethylaminoethyl n-propyl-(alpha-thienyl)methylacetate hydrochloride.

13. 2-diethylaminoethyl benzyl-(alpha-thienyl)methylacetate hydrochloride.

14. 2-diethylaminoethyl cyclohexylmethyl-(alpha-thienyl)methylacetate hydrochloride.

FREDERICK F. BLICKE.
